Inventor:

UNITED STATES PATENT OFFICE.

ALBERT BEYER, OF COLEMAN, TEXAS.

ADJUSTABLE TONGS.

1,105,875.

Specification of Letters Patent.

Patented Aug. 4, 1914.

Application filed August 14, 1913. Serial No. 784,818.

To all whom it may concern:

Be it known that I, ALBERT BEYER, a citizen of the United States, residing at Coleman, in the county of Coleman and State of 5 Texas, have invented certain new and useful Improvements in Adjustable Tongs, of which the following is a specification.

This invention relates to an improvement in tongs and more particularly to tongs of 10 the type used by blacksmiths and the like.

The object of the present invention is the provision of a device of this character of a simple construction which will enable the material to be operated on to be readily 15 grasped and securely held while manipulating the same.

A further object of the invention is the provision of a device of this character which can be readily adjusted to adapt the same to 20 be used upon materials of various sizes.

Other objects of the invention will be apparent from the detailed description herein-after, when read in connection with the accompanying drawings forming a part here- 25 of wherein a convenient embodiment of the invention is shown and wherein like characters of reference refer to similar parts in the several views.

In the drawings: Figure 1 is a side elevation of my improved tongs; and, Fig. 2 is an edge elevation of the same.

Referring now more particularly to the drawings, A designates a stock which is provided with the usual handle portion a and with an enlarged outer end a'. The extreme outer end of the stock A is provided with a bifurcation a² therein and with an opening a³ which extends transversely through the stock and which is positioned adjacent its bifurcated terminal just inward of the bifurcation a². The enlarged end a of the stock A is further provided with a transverse opening a⁴ disposed at right angles to the opening a³ and communicating 40 with the opening a³ heretofore referred to being of greater width than said opening. Slidably mounted in the opening a³ in the stock A is the threaded shank b which projects at substantially right angles from the 45 inner end of a jaw member B which extends substantially parallel to the stock A. The shank b and the opening a³ in the stock A are so formed as to prevent any turning of the shank in said opening. In the particu- 50 lar embodiment illustrated in the drawings, the shank b is provided with flat side

faces which are adapted to lie in close proximity to the side walls of the opening a³ in the shank. It will be understood, however, that the same result may be accomplished 60 in other ways.

Positioned within the transverse opening a⁴ in the stock A is a nut a⁵ which has a threaded engagement with the shank b of the jaw B. As the transverse opening a⁴ in 65 the shank is of greater width than the opening a³ in which the stem b of the jaw B works, it will be seen that the nut will be held against displacement and thus by rotating the same the jaw B may be adjusted 70 transversely of the stock A to any desired extent.

C designates a lever which is substantially co-extensive in length with the shank A, and which is provided with a handle portion c 75 adapted to lie alongside of the handle portion a of the stock A. The outer end of the lever C is arched as at c' to prevent interference with the projecting end of the stem b of the jaw B, and the extreme outer end of 80 said lever is provided with a downwardly turned portion c² which fits within the bifurcation a² formed in the end of the stock, and is pivotally secured therein by a suitable pivot bolt c³. The downwardly extending 85 portion c² of the lever C projects below the bifurcated outer end of the stock C and is provided with a curved or cam-shaped lower edge c⁴ which is positioned directly opposite the engaging surface of the jaw B. 90

The engaging surface of the jaw B may be fashioned in any suitable manner to facilitate its engagement with the material to be operated on. In the embodiment of the invention illustrated in the drawings, the engaging face of the jaw is shown provided with longitudinal and transverse grooves which facilitate the holding of round rods and the like.

In the use of the device the handles c and 100 a of the stock are separated and the material to be grasped is introduced between the engaging surface of the jaw B and the projecting end C² of the lever C. The handles are then brought together which causes the cam 105 face c⁴ of the projecting end c² to engage the material and clamp the same securely against the securing face of the jaw B.

While a convenient embodiment of the invention is illustrated in the accompanying 110 drawings, it will be understood that many changes may be made to the form and con-

struction therein disclosed without departing from the spirit and scope of the invention as defined in the appended claims.

I claim:—

- 5 1. A device of the character described including a stock formed with a transverse opening there being an enlargement formed integral with said stock adjacent the opening, a jaw formed with a threaded shank
- 10 which is adjustably mounted in said opening, the work engaging face of said jaw being disposed substantially parallel with the stock, and a lever having a curved terminal pivotally supported by the stock adjacent
- 15 the jaw whereby said terminal may coact with the jaw to engage the work.

2. A device of the character described including a stock, a jaw, means for adjusting said jaw transversely of the stock, the terminal of said stock adjacent the jaw being 20 bifurcated, a lever pivoted between the bifurcations of said stock, one terminal of said lever being rounded and movable in the same plane as the jaw to coact with the same to engage the work.

25

In testimony whereof I affix my signature in presence of two witnesses.

ALBERT BEYER.
